UNITED STATES PATENT OFFICE.

ADOLF GRAETZ, OF BERLIN, GERMANY, ASSIGNOR TO THE ERA INCANDESCENT OIL LAMP COMPANY, LIMITED, OF LONDON, ENGLAND.

INCANDESCENT LAMP.

SPECIFICATION forming part of Letters Patent No. 619,165, dated February 7, 1899.

Application filed February 3, 1897. Serial No. 621,775. (No model.)

To all whom it may concern:

Be it known that I, ADOLF GRAETZ, a subject of the King of Prussia, German Emperor, and a resident of Berlin, in the Kingdom of Prussia, German Empire, have invented certain new and useful Improvements in Hydrocarbon or Petroleum Lamps, (for which I have obtained Swiss Patent No. 13,931, dated January 30, 1897,) of which the following is an exact specification.

This invention has for its object to produce hydrocarbon or petroleum lamps giving a non-luminous flame, so that such lamps can be employed for use in incandescent gas-lighting. Heretofore common illuminating-gas has chiefly been used for heating incandescent devices, stockings, hoods, or mantles, so that they emit light.

By my improved lamps I am able to use hydrocarbons or petroleum for heating incandescent devices, whereby a great saving is effected, and, further, I am able to produce incandescent lights at any desired place without necessitating the existence of gas-works.

My improvements in petroleum-lamps of said kind relate to certain combinations and arrangements of parts, as are fully described hereinafter; and the purpose of my improvements is to render the ignition of the lamp more easy and to make the various parts of the burner accessible without necessitating a removal of the incandescence body from the chimney or from the gallery of the burner, respectively.

In order to make my invention more clear, I refer to the accompanying drawings, in which similar letters denote similar parts throughout the different views, and in which—

Figure 1 is a vertical section through the improved burner. Fig. 2 is a horizontal section taken on line 8 9 of Fig. 1. Fig. 3 is also a horizontal section, or, more precisely, represents two such sections, taken on line 10 11 of Fig. 1. Fig. 4 is a view similar to Fig. 1, but showing the lamp combined with a mechanism for raising the gallery and other parts. Fig. 5 shows the gallery raised by the mechanism aforementioned. Fig. 6 is a view similar to Fig. 5, but showing the gallery separated from said mechanism; and Fig. 7 is a plan of the burner and gallery employed in

the form of construction shown in Figs. 4 to 6, the chimney, the incandescence body, and the flame-disk of the burner being removed.

My improved burner is constructed as follows: To the oil-reservoir is attached a burner-casing whose lower portion is perforated. Through these perforations enters the air. The wick *a*, Fig. 1, or the two concentric tubes *a' a²*, inclosing said wick, respectively, is or are encompassed by two concentric caps *e e'*, that form two annular channels or flues, the inner channel being formed by or between the cap *e* and the upper end of the wick-tube *a'* and the outer channel being formed by or between said two caps *e e'*. A particular feature of these caps is that they are of uniform height, so that the draft produced within the two channels or flues is of the same strength. There is of course an annular space between the upper ends of the caps *e e'*, and there are apertures *e²* in the lower portion of the cap *e* and apertures *e³* in the lower portion of the cap *e'*. Therefore the air passing through the apertures *e²* escapes partly through the outer annular flue and partly through the apertures *e³*. This second portion of the air flows upward between the chimney *i* and the incandescent device *o*, which latter is suspended from an annular rod *o'*, fixed in position by means of a screw *o²*. The incandescent device *o* takes with its lower end over the upper end of the cap *e'* and is, in fact, supported not by said rod *o'* only, but by the cap *e'* too.

Besides the two caps *e e'* aforementioned there is provided a third cap *u*, which extends upward from the inner wick-tube *a²* and is supported by this tube. The cap *u* carries the flame-disk *u'*, which is situated between the closed top of the cap in question and the plane of the upper ends of the caps *e e'*. The mantle portion of the cap *u* is provided with apertures *u²*, that are situated not only below the flame-disk *u'*, but also above the same. The diameter of the cap *u* is smaller than that of the wick-tube *a²*—or, in other words, that cap is contracted at *u³*, this plate *u³* being situated in close neighborhood to the upper end of said wick-tube. The burning gas issuing from the wick *a* receives thus air through the inner annular flue formed by or between the upper end of the wick-tube *a'* and the cap *e*.

- and through the lower apertures of the cap u —i. e., through those apertures which are situated below the flame-disk u' . The non-luminous flame thus produced passes through 5 the annular space between the edge of the flame-disk u' and the opposite edge of the cap e' , and when leaving said space the flame receives a second supply of air, this second supply taking place through the outer annular flue formed by or between the caps e and e' and through the upper apertures of the cap u —i. e., through those apertures which are situated above the flame-disk u' . This 10 twofold supply of air is a characteristic feature of my invention, and I wish it to be understood that said twofold supply of air is to take place in any case not from the outer side only, but from the inner side too—i. e., from the caps e e' as well as from the cap u . 15 The particles of gas that are still unburned on passing through the annular space between the edges of the cap e and the flame-disk u' are completely burned on getting mixed with the hot air issuing from the outer annular flue and from the uppermost apertures of the cap u , and there results an extremely hot 20 flame, which is practically colorless and which causes the incandescent mantle to glow with an extreme brilliancy. 25 In order to facilitate the cleaning of the wick and the ignition of the same or of the lamp, respectively, I prefer to combine the arrangements aforescribed with a device for raising the gallery of the lamp, together 30 with the chimney, the incandescent mantle, and the caps e e' , up to such a height that the cap u may be drawn out of the inner wick-tube and removed from the burner; and I further prefer to effect the connection between 35 40 said lifting device and the gallery in such a way that the gallery may be easily disconnected from and as easily connected with said device, as is all fully described hereinafter.
- Referring to Figs. 4, 5, and 6, the lower or main portion a^3 of the burner-casing is provided with two bearings r r' , Fig. 6, holding a shaft r^2 . Two curved levers s , having each a slot s' , Fig. 5, are fixed to said shaft, and said slots take over pins x , Fig. 6, secured to 45 vertical rods x' . The latter may be placed in guides x^2 , Fig. 6, and are displaced by turning the shaft r^2 in one or the other direction, when the levers s or the slots s' of the same, respectively, will take the pins x with them, 50 and will thus cause the vertical movement of the rods x' . The latter support and are connected by a ring z , Fig. 6, provided with 55 hooks z' .
- The bottom a^4 of the gallery is provided 60 with apertures a^5 , Figs. 6 and 7, for letting pass the hooks z' aforesaid. Said apertures terminate into slits a^6 . After the gallery is placed upon the lifting device, or, more precisely, after the bottom a^4 of the gallery is put upon the ring z of said device, in 65 such a manner that the hooks z' of said ring

take through the apertures a^5 of said bottom, the gallery is turned in such a direction that the slits a^6 take below the hooks z' , as shown in Fig. 7. The gallery is then securely connected with the lifting device and may, if desired, be easily disconnected and removed from the same by being turned in the other direction, as will be clear without any further explanation. 70

I am aware of the fact that the described device for connecting and disconnecting the gallery is old, and I do not claim it. 75

Having thus fully described the nature of my invention, what I desire to secure by Let- 80 ters Patent of the United States is—

1. A hydrocarbon or petroleum lamp producing a non-luminous flame for use in incandescent gas-lighting, consisting of a reservoir with perforated burner-casing and concentric wick-tubes attached thereto, two concentric caps e , e' of uniform height forming an annular air-space between their upper ends, aperture e^2 in lower portion of cap e and aperture e^3 in lower side portion of cap e' , an air-channel formed by cap e and the outer wick-tube, a contracted cap u with perforated mantle secured to the inner wick-tube and carrying a flame-disk, an incandescent device and a chimney; whereby the air passing through the burner-casing is divided, it passing partly within the inner wick-tube through the perforations in mantle of cap u , below and above the flame-disk, partly through the channel formed by cap e and the outer wick-tube, partly through the annular space between caps e , e' and partly through apertures e^2 , e^3 and then between the chimney and the incandescent, as specified. 90

2. In an incandescence lamp a novel draft arrangement composed of a perforated burner-casing, two concentric wick-tubes, two concentric caps e , e' of uniform height forming an annular air-space between their upper ends, the aperture e^2 in the lower portion of cap e and the aperture e^3 in the lower side portion of cap e' , an air-channel formed by cap e and the outer wick-tube, a contracted cap u with perforated mantle secured to the inner wick-tube and carrying a flame-disk, an incandescent device and a chimney; whereby the air passing through the burner-casing is divided, it passing partly within the inner wick-tube through the perforations in mantle of cap u , below and above the flame-disk, partly through the channel formed of cap e and the outer wick-tube, partly through the annular space between caps e , e' and partly through the apertures e^2 , e^3 and then between the chimney and the incandescent, as specified. 100

In testimony whereof I have signed this specification in the presence of two subscribing witnesses.

ADOLF GRAETZ.
